[57] CLAIM

The ornamental design for a vehicle gas filler cover, as shown and described.

DESCRIPTION

FIG. 1 is a front perspective view of a vehicle gas filler cover showing my new design;

FIG. 2 is a reduced top view of the cover of FIG. 1;

FIG. 3 is a reduced front view of the cover of FIG. 1;

FIG. 4 is a reduced bottom view of the cover of FIG. 1;

FIG. 5 is a reduced side view of cover of FIG. 1; and,

FIG. 6 is a reduced rear view of the cover of FIG. 1.

The broken line showing of environment is for illustrative purposes only and forms no part of the claimed design.
